CLAIM

The ornamental design for a foldable keyboard, as shown and described.

DESCRIPTION

FIG. 1 is a front perspective view of a foldable keyboard in the open position, showing our new design;

FIG. 2 is a front perspective view thereof folded in the closed position;

FIG. 3 is a top view thereof in the open position;

FIG. 4 is a front view thereof in the open position;

FIG. 5 is a right side view thereof in the closed position;

FIG. 6 is a rear view thereof in the open position;

FIG. 7 is a left side view thereof in the closed position; and,

FIG. 8 is a bottom view thereof in the open position.

The cord is shown broken away in the views in order to show an indeterminate length.
